MAGNETO GENERATOR

Edward B. Nowosielaki, Sidney, N. Y., assignor, by
mesne assignments, to Bendix Aviation Corporation,
South Bend, Ind., a corporation of Delaware

Application April 21, 1934, Serial No. 721,746

8 Claims. (Cl. 123—149)

The present invention relates to a magneto generator and more particularly to a high tension magneto adapted to furnish ignition current for internal combustion engines.

5 It is an object of the present invention to provide a novel high tension magneto generator which is efficient and reliable in operation and simple and economical in construction and assembly.

10 It is another object to provide such a device which is especially adapted for operation at high rotative speeds.

15 It is a further object to provide such a device which embodies a single coil, breaker mechanism and condenser, with a novel arrangement for furnishing ignition for an engine having more than one cylinder.

20 It is another object to provide such a device in which a distributor for the high tension current is built into the rotor of the magneto.

25 It is another object to provide such a device in which the engine flywheel, the rotating magnet, the breaker cam and distributor ring are all incorporated in a single rotating unit so that there is only one rotating part in the device.

30 Further objects and advantages will be apparent from the following description taken in connection with the accompanying drawings in which:

35 Fig. 1 is a perspective view of a preferred embodiment of the device with the rotor removed from the housing in order to expose the parts;

Fig. 2 is substantially an axial section of the device;

35 Fig. 3 is a sectional detail of an output terminal member;

40 Fig. 4 is a diagrammatic illustration of the high tension electrical circuit showing the distributor in position to connect one output terminal member with the high tension terminal of the coil; and

45 Fig. 5 is a view similar to Fig. 4 showing the distributor rotated through 180 degrees so as to connect the other output terminal to the coil.

50 Referring first to Fig. 2 of the drawings, there is illustrated a shaft 1 which may be the extended crankshaft of the engine for which the magneto is to furnish ignition, or which may be directly coupled thereto. Shaft 1 is journaled by means of a suitable bearing structure indicated at 2 in a housing 3 which is arranged to be mounted in any suitable way with provision for rotary adjustment on the engine casing, not shown.

55 A rotor indicated generally at 4 is keyed on the end of the shaft 1 as shown at 5, and is suit-

ably retained thereon as by means of a nut 6. Rotor 4 comprises a disc member 7 which may be the engine flywheel and which is arranged to carry all the rotating elements of the magneto comprising the magnet structure indicated generally at 8 (Fig. 1), the breaker cam 9 and the distributor 11.

The magnet structure comprises straight cylindrical bar magnets 12 arranged in pairs on opposite sides of the axis of the rotor. Like poles 10 of the magnets 12 are received in openings 13 in arcuate pole pieces 14 whereby the magnets are held in assembled position, and pole pieces 14 are retained by cheek pieces 15 and 16 of non-magnetic material having shoulders 17 and 18 co-operating with rabbets 19 and 21 at the edges of the pole pieces. The magnet assembly is mounted on the flywheel 7 by means of rivets 22, the cheek piece 16 being arranged to space the magnet structure sufficiently from the flywheel 20 to magnetically insulate the same. This arrangement permits the flywheel to be made from magnetic material such as steel capable of withstanding the stresses set up by rotation at high speeds.

25 The cheek piece 15 is preferably formed to provide the breaker cam structure 9 integral therewith although the cam may of course be formed as a separate element fixed thereto if deemed desirable.

30 A stator comprising arcuate pole shoes 24 and 25 and a connecting core member 26 (Fig. 2) is mounted in the housing 3 as by means of rivets 27 and spacing members 28. The pole shoes 24 and 25 are arranged with their inner surfaces 35 concentric with the pole pieces 14 of the rotor magnet whereby rotation of the magnet causes reversals of flux through the external magnetic circuit 24, 26, 25.

35 An induction coil 29 is mounted on the core 26 and is provided with the usual primary coil 31 and secondary coil 32 having a high tension terminal 33. One end of the primary coil is grounded in the usual manner, and the opposite end is connected by a lead 34 to the ungrounded terminal 35 of a condenser 36, and by a lead 37 to a breaker mechanism including an insulated breaker arm 38. The breaker arm comprises a cam follower 39 adapted to cooperate with the breaker cam 9 and thereby cause contact 41 on the breaker arm 38 to engage and disengage an adjustable grounded contact 42.

40 The magneto here illustrated is adapted to furnish ignition for a two cylinder engine, and two output terminal members 43 and 44 are therefore

provided for furnishing connections to the spark plug cables of the engine, not illustrated. The output terminals are preferably constructed as shown in Fig. 3 with an opening 45 for the spark plug cable and a spring pressed brush 46. The output terminals are mounted in the housing, being suitably retained therein as by means of cap screws 47 in such position that the brushes 46 thereof are positioned substantially in the same transverse plane as the high tension terminal 33 of coil 29 and at the same radius from the axis of the rotor.

In order to periodically connect the output terminals 43 and 44 with the high tension terminal 33 of the coil, a distributor structure is provided comprising a block of insulating material 48 mounted in a circular recess 49 in the flywheel 7, and arcuate conductors 51 and 52 embedded in the insulating block in position to engage or substantially engage said terminals and form electrical connections therebetween at certain angular positions of the rotor.

By reference to Fig. 4, it will be seen that at one angular position of the rotor the distributor conductor 51 connects the high tension coil terminal 33 with the output terminal 43, and when the rotor has turned through 180 degrees as shown in Fig. 5, the other rotor conductor 52 serves to connect the coil terminal with the output terminal 44. It will be understood that the distributor conductors 51 and 52 and the breaker cam mechanism 9, 39, etc., are so arranged as to cause the primary of the induction coil to be broken, and the high tension circuit to be closed at the proper angular positions of the rotor magnet with respect to the pole shoes 24 and 25 to secure the optimum result. It will be understood that the housing 3 may be rotarly adjusted as by means of a handle 53 to adjust the timing of the ignition in accordance with the operation of the engine.

Although but one embodiment of the invention has been shown and described in detail it will be understood that other embodiments are possible and various changes may be made in the details and arrangements of the parts without departing from the spirit of the invention as defined in the claims appended hereto.

What is claimed is:

1. In a high tension magneto generator for internal combustion engines a housing, a rotor journalled therein including a permanent magnet and forming a closure for the housing, a stator in said housing including pole shoes adapted to cooperate with the rotating magnet and an induction coil having a high tension terminal, insulated output terminal members in said housing and means on said rotor for periodically providing an electrical connection from the coil terminal to said output terminals.

60 2. In a high tension magneto generator for internal combustion engines a housing, a rotor journalled therein including a permanent magnet and forming a closure for the housing, a stator in said housing including pole shoes adapted to cooperate with the rotating magnet and an induction coil having a high tension terminal, insulated output terminal members in said housing, said rotor having conducting means mounted thereon for connecting the coil terminal to said output terminals at predetermined angular positions of said magnet.

65 3. In a high tension magneto generator for internal combustion engines a housing, a rotor journalled therein including a permanent magnet and a breaker cam, a stator in said housing

including pole shoes adapted to cooperate with the rotating magnet and an induction coil having a high tension terminal, means including a cam follower on the housing for periodically breaking the primary circuit of the induction coil, insulated output terminal members in said housing having contacts located substantially in the same transverse plane as the coil terminal, and insulated conducting segments carried by said rotor and arranged to connect the coil terminal 10 with the output terminals at predetermined angular positions of the magnet with respect to the stator pole shoes.

4. In a magneto generator for internal combustion engines a housing, a rotor journalled 15 therein including an engine flywheel, a permanent magnet non-magnetic means rigidly connecting the magnet to said flywheel in spaced relation thereto and a breaker cam mounted coaxially thereon, a stator including pole shoes and a connecting core member with an induction coil thereon fixed to the housing and spaced therefrom in position to cooperate with the rotating magnet, a cam follower pivoted in the housing in position to cooperate with the breaker cam, 25 means including contacts operated by said cam follower to open and close the primary circuit of said coil, output terminal members mounted in spaced relation in said housing and means on said rotor for periodically connecting the output 30 terminal members to the high tension terminal of said coil.

5. In a magneto generator for internal combustion engines a housing, a rotor journalled 35 therein including an engine flywheel, a permanent magnet non-magnetic means rigidly connecting the magnet to said flywheel in spaced relation thereto and a breaker cam mounted coaxially thereon, a stator including pole shoes and a connecting core member with an induction coil 40 thereon fixed to the housing and spaced therefrom in position to cooperate with the rotating magnet, a cam follower pivoted in the housing in position to cooperate with the breaker cam, means including contacts operated by said cam 45 follower to open and close the primary circuit of said coil, output terminal members mounted in spaced relation in said housing, said flywheel having a circular recess, and arcuate conductors fixed in said recess insulated from the flywheel 50 adapted to cooperate periodically with the high tension terminal of said coil and said output terminal members.

6. In a magneto generator for internal combustion engines a unitary rotor element including 55 an engine flywheel and a permanent magnet fixed thereto, a stator including an induction coil having a high tension terminal and arranged to be energized by rotation of said magnet, said flywheel having a circular recess, a block of insulating material fixed in said recess, stationary output terminals having contacts arranged substantially in a circle with said coil terminal about the rotor axis, and arcuate conductors mounted on said insulating block arranged to connect said 65 output terminals to said coil terminal at predetermined angular positions of the rotor.

7. In a high tension magneto generator for internal combustion engines a housing, a rotor journalled therein including an engine flywheel, 70 a permanent magnet and a breaker cam, a stator in said housing including pole shoes adapted to cooperate with the rotating magnet and an induction coil having a high tension terminal, means including a cam follower on the housing 75

for periodically breaking the primary circuit of the induction coil, insulated output terminal members radially disposed in said housing, said flywheel having arcuate conducting means positioned thereon for selectively connecting the coil terminal to said output terminals in sequence when the primary circuit of the coil is broken.

8. In a magneto generator for internal combustion engines a unitary rotor element including an engine flywheel, a permanent magnet, non-magnetic means for rigidly mounting the

magnet on the flywheel in spaced relation thereto, a stator including an induction coil having a high tension terminal and arranged to be energized by rotation of said magnet, output terminals having contacts arranged substantially in the same transverse plane as said coil terminal, arcuate conductors on said flywheel insulated therefrom for periodically forming an electrical connection between said high tension coil terminal and said output terminals in sequence.

EDWARD B. NOWOSIELSKI.
